UNITED STATES PATENT OFFICE.

FREDRIK LJUNGSTRÖM, OF LIDINGO-BREVIK, SWEDEN, ASSIGNOR TO AKTIEBOLAGET LJUNGSTRÖMS ÅNGTURBIN, OF STOCKHOLM, SWEDEN, A CORPORATION.

LOCOMOTIVE PROVIDED WITH AIR-COOLED CONDENSER.

Application filed April 3, 1922. Serial No. 549,260.

To all whom it may concern:

Be it known that I, FREDRIK LJUNGSTRÖM, chief engineer, subject of the King of Sweden, residing at Lidingo-Brevik, Stockholm, Sweden, have invented certain new and useful Improvements in or Relating to Locomotives Provided with Air-Cooled Condensers, of which the following is a specification.

10 In locomotives provided with air-cooled condensers it has previously been suggested to effect the passage of the cooling air through the condenser by means of fans, the supply of the air to the fans being facilitated by the aid of a separate air catching device. These fans are actuated by means of one or more of the movable members of the locomotives, as for instance by gearing connected with the driving wheels or their driving mechanism. Since in such case the quantity of the cooling air passing through the condenser depends upon certain circumstances, as for instance the speed of the locomotive, the driving mechanism of the 25 fans and the air catching devices have been so constructed that at every moment only the necessary quantity of air is caused to pass through the condenser. This problem has, for instance, according to the U. S. Patent No. 1,371,178, been solved by a controlling apparatus controlling the driving mechanism of the fans and the position of the air catching devices in such a manner that the ratio of speed of the fans to that of the 30 locomotive and the position of the air catching devices are varied upon variations of the speed of the locomotive. The said controlling apparatus is in this case adjusted by means regulated by the difference of pressure of the current of air forced through the condenser by the fans, said difference existing at two spaced points in the air-cooled condenser.

According to Patent No. 1,371,178 said 45 controlling apparatus consists of a servomotor actuated by said difference of pressure and in turn moving frictional disks towards or from the centers of the fans, said disks rolling on plane disks connected with the fans, the speed of rotation of the fans thus being varied.

In this arrangement, however, the object of which is to bring about a current of air

suitable at all events, the variations of the speed of the fans or of the quantity of air forced by the same can only be effected within certain bounds corresponding to the outer and inner limiting positions of the frictional disks, this circumstance being particularly effective in case the fans are actuated by the aid of the driving wheels of the locomotive.

This will entail certain inconveniences in the operation of an air-cooled condenser of the type in question. The driving mechanism of the fans may in certain cases, as for instance upon low speed of the locomotive, obtain too small a speed, so that the controlling apparatus cannot give the fans the speed necessary for effecting the necessary current of air, whereas upon high speed of the locomotive the contrary is the case. Besides the temperature of the cooling air can exert an influence on the magnitude of the necessary quantity of air, a high air temperature requiring an increased quantity of air, while at lower air temperature a less quantity of air will suffice.

Of course, the greatest necessary quantity of air would be sufficient on all occasions. The operation of a device giving this greatest necessary quantity of air would, however, necessitate a useless work of the fans and consequently reduce the useful effect of the whole plant. The object of 55 condensers in connection with locomotives is, however, to improve the total effect of the locomotive and to construct every detail of the condenser in such manner that the same contributes to a saving of work, and since it has proved necessary, in order to obtain a good vacuum in such a condenser during a long drive, to use fans, the work of the same has to be reduced as far as 60 possible.

This invention relates to an arrangement in locomotives provided with air-cooled condensers and has for its object to attain the lastnamed purpose and at the same time to prevent the abovenamed inconveniences. Thus by the aid of this invention, the fans may be caused to operate only in case a supply of air to the condenser is required, the quantity of air flowing through the condenser being at the same time so adjusted 100 as not to be too great, since in such case a

useless work will be expended in forcing the air through the condenser. On the other hand the quantity of air can be kept at such a magnitude as to be sufficient for cooling the condenser, thus maintaining the vacuum prevailing in the same.

According to the invention said objects are obtained by providing means at the driver's cabin through which the speed of the fans and the capability of the air catching apparatus may be adjusted jointly and dependently or separately and independently of each other. Besides the bounds within which the relative speed of the fans and of the locomotive is varied may be variable and adjustable from the driver's cabin by means of any apparatus devised for the purpose.

An embodiment of the invention is illustrated in the accompanying drawings showing locomotives provided with air-cooled condenser to which the invention is applied.

Fig. 1 is in part a side view and in part a vertical section of such a locomotive. Fig. 2 is a horizontal section of the condenser carriage on line A—A in Fig. 1. Figs. 3 and 4 are similar views of another locomotive. Fig. 5 is a detail view partly in section of the control means for the fans.

Referring to Fig. 1, 1 denotes the boiler supported by a separate boiler carriage 2 on which the driver's cabin 3 is located. Placed on the condenser carriage 4 is, besides the air-cooled condenser 5 the driving engine 6 of the locomotive consisting in this case of a turbine from which movement is transferred to the driving wheels 7 by means of toothed gearings and coupling rods. The air to be supplied to the fans 9 is caught by the blinds 8, enters below the fans and is forced by the latter from below and upwards through the air-cooled condenser 5. The fans 9 are actuated in known manner by friction disks 11 mounted on the shaft 10 rolling on planes rigidly connected with the fans, the speed of the fans in relation to the driving wheels 7 being varied by the disks 11 being moved and thereby caused to approach the centers or the peripheries of the fans. Through the box 12, the shaft 13 and the gear box 14 the driving power actuating the fans is taken from a shaft pertaining to the toothed main gearing. The box 12 contains devices so arranged that the disks 11 in connection with the shaft 10 may be moved so as to vary the speed of the fans in relation to the driving wheels.

The controlling means for the shaft 10 and disks 11, is shown diagrammatically in Figs. 1 to 4, and in detail in Fig. 5, and from Fig. 5 it may be seen that the variation or adjustment of the disks 11 may be effected by the aid of a centrifugal governor 12^a, one of the shafts of the fans being provided with a driving disk 15 from which for in-

stance a wire 15^a transfers movement to a corresponding disk 16 located on the base 12 and connected with the centrifugal governor 12^a that is associated with the same for actuating the disks 11 in the following manner. The centrifugal governor is pivotally connected to a bell-crank-lever 12^b, one arm of which has a sleeve 12^c slidably mounted on the long arm 12^d of a second bell-crank-lever. The second bell-crank-lever has a short arm 12^e carrying a roller 12^f about which extends a control cord 12^g. One end of this control cord is connected to a lever 12^h that may be manually operated by the wheel 17. The other end of the cord is connected by a spring 12ⁱ to the rod of a valve 12^k that is mounted in the box 12. This valve controls ports 12^l through which a pressure medium is admitted to and discharged from a U-shaped chamber 12^m within the box 12. When the valve is in the position shown in Fig. 5, the ports 12^l are closed, but when the valve is shifted upwardly or downwardly, it will open one or the other of these ports and admit pressure fluid into one end of the piston chamber 12ⁿ and discharge or exhaust fluid from the other end of said chamber. In this way the piston 12° which is connected to the shaft 10, is actuated. Said shaft has a spline 12^p that slides through and drives a gear 12^q, which is driven from the shaft 13. If the speed of the locomotive be decreased the piston 12° in the box 12 causes the disks 11 to move towards the centers of the fans to a certain position of maximum speed. If the speed of the train be decreased to such amount that the speed of the disks 11 does not suffice to give the fans the necessary speed, the limiting position can be moved by turning a hand-wheel 17 either so as to move the disks 11 nearer to the centers or to give the shaft 10 a different movement. The reverse will be the case if the speed of the locomotive is too great.

Fig. 2 illustrates how the blinds 8 by means of a hand-wheel 18 are adjustable from the driver's cabin without being automatically opened or closed simultaneously with the variation of the speed of the fans, since it may be of advantage to be able to regulate the catching device independently of the fans, for instance in case of a violent wind blowing against one side of the locomotive and blowing out through the catching device of the other side thus interfering with the operation of the fans. For the same reason the catching devices of both sides may preferably be adjustable independently of each other from the driver's cabin. Consequently the regulating device 12 determines the speed of the fans in relation to the speed of the locomotive within certain limits, and it is incumbent on the employees in the driver's cabin to judge by observing the

vacuummeter of the condenser whether the quantity of cooling air is to be increased or decreased by moving the limiting positions in either direction.

5 Figs. 3 and 4 illustrate the invention as applied to the regulating mechanism mentioned above and described in Patent No. 1,371,178. 12 is the servo-motor moving by means of the piston 20 the disks 11 towards or from the centers of the fans. According to the patent the regulation is so effected that on the middle speed of the locomotive a normal quantity of air is always forced through the condenser. By means of a hand 10 wheel 21 accessible from the driver's cabin a member actuating the servo-motor, as for instance a centrifugal governor as in Fig. 5, is so adjusted that the medium quantity of air may be admitted also at speeds of the 15 locomotive other than the normal one. By the aid of this invention the device may be so arranged that a greater quantity of air than the normal one can be forced through the air cooled condenser 5 on decreased speed 20 of the locomotive, while a smaller quantity of air can be forced through the condenser on increased speed of the locomotive. 25

Figs. 3 and 4 illustrate besides how the blinds are regulated from the same apparatuses 12 and 20 regulating the relative speed of the fans. In said figures blinds are shown as being of plane shape and each rotatable about a point 22. Other forms of the blinds are however conceivable, for instance as shown in the lower part of Fig. 2 at 25.

The invention may be combined with any other driving device and reversing mechanism for the fans than those shown in the 40 drawings. Thus for instance the driving device can be arranged according to the Patent No. 1,371,178, where the reversing of the friction disks is effected by adjusting the disks to oblique position and bending the 45 shaft supporting the same.

What I claim as new and desire to secure by Letters Patent of the United States is:—

1. In locomotives provided with an air-cooled condenser and fans effecting an air flow through the condenser, said fans being driven by one of the movable parts of the locomotive, the arrangement that the fans are driven by the aid of an apparatus changing its position according to the speed of the locomotive in such a manner that the ratio of speed between the fans and the locomotive is varied upon variations of the speed of the locomotive, and means associated with said apparatus for manually controlling the speed of said fans. 50 55 60

2. In locomotives provided with an air cooled condenser and fans effecting an air flow through the condenser, said fans being driven by one of the movable parts of the locomotive, the arrangement that the fans are driven by the aid of an apparatus including a centrifugal governor changing its position according to the speed of the locomotive in such a manner that the ratio in speed between the fans and the locomotive is 65 70 75 varied upon variations of the speed of the locomotive, and means associated with said apparatus for manually controlling the speed of said fans.

3. A locomotive as claimed in claim 1 including a centrifugal governor forming part of said apparatus and adapted to automatically control the speed of said fans. 75

4. A locomotive as claimed in claim 1 including air deflecting plates associated with said condenser and manually controlled means for controlling said air deflecting plates. 80

In testimony whereof I affix my signature in presence of two witnesses.

FREDRIK LJUNGSTRÖM.
